UNITED STATES PATENT OFFICE

2,407,331

GLASS BULB AND FLASK HOLDER

Harry L. Van Velzer, State College, Pa.

Application March 1, 1945, Serial No. 580,453

5 Claims. (Cl. 294—20)

(Granted under the act of March 3, 1883, as
amended April 30, 1928; 370 O. G. 757)

1

The invention described herein may be manufactured and used by or for the Government for governmental purposes, without the payment to me of any royalty thereon.

The invention to be hereinafter described relates to bulb gripping and holding devices.

There are many devices provided with resilient members for receiving therebetween and yieldingly holding bulbs, such as electric light bulbs, and various other objects of a somewhat similar frangible nature. An objection to most of them is that they are not adjustable to objects of varying sizes to any considerable extent. A further objection to many is that though they may be spread to receive objects of increasing size, they can not be contracted about such larger objects or, in fact, about any object received therein.

The present invention is constructed and designed to avoid the above and other objections and provide a simple, efficient, compact and durable bulb gripping and holding device which may be produced at low cost from readily obtainable materials.

In order to more clearly disclose the construction, operation and use of the invention, reference should be had to the accompanying drawing forming part of the present application. Throughout the several figures of the drawing like reference characters designate the same parts in the different views.

In the drawing:

Fig. 1 is a central longitudinal cross section, showing only the two operative gripping parts that would appear in elevation;

Fig. 2 is a top plan view of Fig. 1, omitting the flexible gripping members and the spreader; and

Fig. 3 is a right hand end elevation of the spreader.

In Fig. 1 the invention is shown in its full operative gripping and holding position.

Referring to the drawing in detail, 1 and 1a indicate, respectively, outer and inner tubular members of a telescopic handle. The outer or free end of 1a is closed by a tubular plug 2 having a flanged and knurled head 3 and an exteriorly threaded body 2a of reduced diameter and appreciable length. Plug 2 is swivelled into the outer end of 1a by one or more small set screws, pins or the like extending through the wall of 1a and into an annular groove or channel in 2. This, of course, locks the plug in the free end of 1a and prevents its removal or any longitudinal movement. On the other hand, it permits unlimited rotation of 2 within 1a.

Mounted within 1a is a longitudinally movable 58 tube 4 and the telescoped part of inner tube 1a

2

cup 4 of approximately the same length as the body 2a of the plug. It is of a diameter to fit over 2a and interiorly threaded with threads complementary to those on 2a. It is adapted to receive and cooperate with 2a. Radially directed studs, pins, set screws or the like 5 extend from its side walls playing freely in the longitudinal slot 6 of 1a.

As 2 is rotated it will, of course, feed 4 longitudinally of 1a in one direction or the other according to the direction of rotation, the extent of such feed or travel corresponding to the number of rotations of 2. The longitudinal feed of cup 4 affects the operations of the gripping and holding elements or features, as will be more fully disclosed hereinafter.

In the opposite end of 1a are mounted the inner ends of a plurality of flexible gripping or jaw members or elements 7. They may be secured 20 thereto to travel therewith by any suitable and acceptable means. In the instance shown, it is a friction fit. Preferably, these gripping members are leather in the form and shape known and used as V-belt. Their flexibility, preferably, is increased by lateral kerfs or V-notches 8 at frequent and regular intervals throughout their lengths. In the construction shown, four such members are used though it will be well understood that the invention is not in any degree limited to four. Two, only, of the four are shown. A view at right angles to Fig. 1 would show the other two but would add nothing to a clear understanding of the invention. Through each of these members is threaded a strong, small diameter wire 9 such as piano wire, for instance. One end is anchored to the outer end of the respective member 7. The opposite end is extended through the interior of the handle and anchored to the inner end or bottom of cup 4.

By stressing wires 9 jaws 7 will contract upon themselves and toward each other in generally circular paths or directions along the lines of least resistance—i. e. along the notched edges. However, without devices to guide in formation 45 of the curves they will be relatively small in diameter, flat and irregular and the curve of one member may not, necessarily, correspond with that of any other. To avoid these difficulties a spreader has been devised comprising a rod or piston 10 and spider or head 11. Each arm or branch 12 of the spider terminates in a saddle 13 adapted to straddle and receive the V edge of the respective member 7.

Rod 9 extends longitudinally through outer

and between the assembled flexible members 7 within those members. The extreme inner end of rod 10 is yieldingly connected to a radially extending web 14 of a collar or ring 15 carried by one end of the member 1. That part of web 14 connected to 15 extends through and is freely slideable in the slot 6. However, the ring 15 being fixed to 1 travels with it and is stationary with relation thereto. This member 14, on the other hand, is provided with holes or perforations for the free passage of the wires 9 during any telescoping movement of tubes 1 and 1a. A tension spring 16 connects the web 14 with the adjacent end of 10 urging 10 toward 14 in a retracting action. That, in turn draws the spider 11 against the members 7 at points only slightly beyond the outer or free end of 1, thereby spreading them and maintaining them, at that point, uniformly separated or distended, the spider and tube end cooperating in this action.

With the parts in the position of Fig. 1, the jaws are gripping and are securely held about the bulb or other object which would be inclosed by them. To loosen that grip, the head 3 is turned to travel the member 2, 2a toward the jaw end. This removes strain from wires 9 and permits the flexible members 7 to slack, extend or loosen, reducing the gripping action. It also reduces the binding friction between 7 and the end of 1, as will be clear. Then the ring 17, slidably mounted on 1 and provided with radial web 18 extending through aligned slots 6 and 19 in 1a and 1 respectively, and connected to 10, is moved toward the jaw end, against the tension of spring 16. This carries the spreader out of engagement with members 7, allowing them to slacken and collapse.

With the jaws 7 secured in 1a against longitudinal movement therein, the spreader 9-13 in the position of Fig. 1, frictionally binding and locking 7 against the end of 1 and deflecting them to open or spread position, and the wires 9 under the desired tension, the curved jaws formed by the members 7 become substantially rigid.

Rigidity, however, is not imparted until the necessary tension is exerted. That tension is imparted by drawing the cup 4 toward the head 3 of plug 2, as previously stated. The requisite travel of 4 along 2a of 2 to create the desired tension may be altered by various circumstances and conditions, including the degree, amount or extent of spread or curvature of the members 7 in forming the jaws for the respective use. The threaded connection amply provides for establishing the respective desired tension under any and all circumstances for all uses or applications for which the device has been devised.

As will be well understood, the members 1 and 1a are each provided with diametrically placed slots 6 and 19 for free travel of the webs 14 and 18. While pairs of such slots have been shown and are preferable, more may be used.

Rod 10 may be secured to web 18 in any manner desired as by soldering, welding, riveting etc. In assembled relation it has an easy sliding position centrally within the handle and between the inner edges of the members 7, a very gradual and slightly increasing radial space resulting between 7 and 10, longitudinally of 10 in the direction of the spider 11 from the end of 1a to the end of 1, due to the slightly greater diameter of 1.

It is thought that the construction, operation and use of the invention will be clear from the preceding detailed description.

Many changes may be made in the construction, arrangement and disposition of the various parts of the invention within the scope of the appended claims without departing from the field of the invention and it is meant to include all such within this application wherein only one preferred form has been illustrated, purely by way of example and with no thought or intent of, in any degree, limiting the invention thereby.

Having thus described my invention what I claim and desire to protect by Letters Patent is:

1. In combination in a bulb holding device, a tubular handle, flexible holding members mounted therein and extending therebeyond to provide gripping jaws, means extending through said flexible members and therebeyond within said handle, means stressing said last named means and means movable within said handle between said flexible holding members and yieldably engaging and spreading said flexible members adjacent and exterior to said handle.

2. In combination in a bulb holding device, a tubular handle, flexible holding members mounted therein and extending therebeyond to provide gripping jaws, means extending through said flexible members and therebeyond within said handle, means stressing said last named means, means movable within said handle between said flexible holding members and engaging and spreading said flexible members adjacent and exterior to said handle, and means for releasing said engaging and holding means.

3. A bulb holding device comprising a hollow handle member, flexible gripping members secured at one end within the handle and extending therefrom, flexible tension means positioned within the gripping members and secured to the outer ends of the gripping members and adapted upon tensioning to vary the conformation thereof, and means positioned on the handle and connected to said tension means for varying the tension on the tension means, whereby the pressure exerted on a bulb by the gripping members may be varied.

4. The structure as claimed in claim 3, including a spreader positioned between the gripping members and yieldingly adjustable with respect thereto to adapt the gripping members to engage bulbs of different sizes.

5. A bulb holding device comprising a hollow handle member, a plurality of flexible gripping elements having their inner ends secured within the handle member and extending therefrom, tensioning elements respectively positioned within the gripping elements and connected thereto at the outer ends of the gripping elements, adjusting means on the handle connected to the tensioning elements for varying the loading thereof to thereby vary the conformation of the gripping elements, a sleeve slidably mounted on the handle member and engaging the exterior of the gripping elements, a spreader movable longitudinally with respect to the handle and engaging the inner surfaces of the gripping elements and a yielding connection between the spreader and said sleeve member.
